RADIATOR FILLING DEVICE

Harry C. Mougey, Detroit, Mich., and Charles R. Short, Clermont, Fla., assignors, by mesne assignments, to General Motors Corporation, Detroit, Mich., a corporation of Delaware

Original application September 22, 1927, Serial No. 221,227. Divided and this application June 3, 1932, Serial No. 615,086

8 Claims. (Cl. 257—125)

This invention relates to improvements in filling devices for radiators of the type which are commonly used in connection with cooling systems for internal combustion engines, and this 5 application is a division of our co-pending application, Serial No. 221,227, filed September 22, 1927, now Patent No. 1,865,877, issued July 5, 1932.

An object of the invention is to provide a 10 radiator filling device which is so constructed that when the cooling system is filled with liquid, a space will automatically be left within the top of the radiator to provide for the expansion of the liquid in the cooling system when heated. 15 This is especially desirable when anti-freeze solutions are being used in the cooling system, since when using an ordinary form of radiator filling device, if the liquid is poured into the radiator until it rises substantially to the top 20 of the filling device, there is no space left in the radiator for expansion of the liquid when it becomes heated, and consequently when this expansion occurs, a considerable amount of the anti-freeze solution is sometimes forced out 25 through the overflow pipe.

With the above and other objects in view, our 30 invention will be more clearly understood by referring to the specification and accompanying drawings, in which:

Figure 1 is a front view of a radiator partly 35 in elevation, and partly in section, showing our improved form of filling device associated therewith.

Figure 2 is a sectional view, on a larger scale, 40 of the filling device shown in Figure 1.

Figures 3, 4 and 5 are views corresponding generally to Figure 2, but showing various modified forms of filling devices.

Merely for purposes of illustration, our improved form of filling device has been shown in 45 connection with a cross flow radiator, but it will be understood that it will be just as applicable for use with vertical flow radiators. In the drawings, the reference numeral 10 indicates a radiator having a core portion 12 composed of 50 horizontally extending water tubes or passages 36. These tubes or passages communicate at one side of the radiator with an inlet chamber 16, and at the opposite side of the radiator with 55 an outlet chamber 20. A header portion 21 extends across the top of the radiator above the core 12, and this header portion communicates at one end with the outlet chamber 20. The liquid in the radiator is withdrawn from 55 the outlet chamber 20 through the conduit 38

in the usual manner by the engine water pump (not shown) and after being forced by the latter through the water jacketed space around the engine cylinders where it becomes heated, the cooling liquid is returned to the inlet chamber 16 of the radiator through the conduit 26, in order that it may flow through the tubes or passages 36 to become cooled before returning to the engine.

It is considered desirable to keep the normal 10 liquid level in the radiator slightly above the top of the radiator core so that there will be space left in the top of the radiator for the cooling liquid to be displaced into as it becomes heated and expands. In the ordinary radiator, it is customary 15 for the operator to pour in cooling liquid until the level of the liquid reaches the top of the filler opening, in order to be sure that the cooling system is full. As soon as the engine becomes hot, the water expands and consequently some of it is 20 displaced through the overflow pipe, since there is no space left for the liquid to be displaced into. When the cooling system contains relatively expensive anti-freeze substances, such as glycerine or alcohol, this is very undesirable as it not only 25 wastes the anti-freeze solution, but also is apt to change the percentage of the latter with respect to the amount of water in the cooling system, and thereby permit the radiator or engine to become 30 damaged by freezing.

To prevent this, we construct the radiator filling device in such a manner that an expansion space is automatically provided at the top of the radiator in the header portion 21. Our improved form of filling device consists of a filler tube 50 which is secured in the top of the radiator and which extends downwardly into the header portion to a point slightly above the top of the radiator core 12. Secured in the tube is a support 52 having a squared opening 54 formed in it. Slidably held in the opening 54 is a squared portion 56 formed on a rod 58 which at its lower end is secured in any suitable manner to a washer 60. Fastened on the rod above the support 52 is a stop 61 which limits the downward movement of the rod. The upper end of the rod is provided with threads adapted to be engaged by a threaded boss 62 formed on the radiator cap 64. A resilient gasket 66 is adapted to be clamped between the bottom of the tube 50 and the washer 60, and a similar gasket 68 is also adapted to be clamped between the top of the tube and cap 64. A sleeve 70 is supported concentrically with the tube 50 and is secured to the bottom of the latter as at 72 in any suitable manner which will provide a 55

water tight connection between the two parts. This sleeve extends upwardly to a point just below the top of the radiator header portion 21. A plurality of openings 74 is provided in the tube 50 just above the point where the sleeve is secured to the tube. The usual overflow pipe 76 passes through the sleeve 70 and communicates with the interior of the tube 50.

When the cap 64 is removed, the rod 58, together with the washer 60 and the gasket 66, will drop downwardly until the stop 61 comes into contact with the support 52. Liquid may then be poured into the tube 50 and will flow through the opening in the bottom of the tube into the radiator until the liquid level reaches a point slightly above the top of the openings 74. As the only escape of the air in the radiator is then sealed shut by the liquid, the remaining air will be trapped above this level and will automatically provide an expansion chamber in the top of the header portion 21. Any additional liquid which is poured into the tube 50 will merely rise in the latter, thereby indicating to the operator that the cooling system is filled to the proper level. He will then replace the cap 64 and in doing so, will draw the gasket 66 and the washer 60 up against the bottom of the tube. Thereafter, the only communication between the inside of the tube 50 and the expansion chamber is through the openings 74, but it will be appreciated that these openings are normally sealed by the liquid which is trapped in the bottom of the tube 50 and in the space between the sleeve 70 and the tube 50.

When the engine becomes heated, the water in the cooling system will expand and will be displaced into the expansion chamber in the header portion 21. The trapped air which the expanding water displaces will be forced through the passage between the sleeve 70 and the tube 50, and through the openings 74, forcing its way through the liquid which is trapped inside the sleeve 70 or the tube 50, after which it may escape to the atmosphere through the overflow pipe 76. It will be readily seen that the level of the liquid in the header portion 21 would have to rise above the top of the sleeve 70 before any of the liquid could be forced out through the overflow pipe. This is quite unlikely as the header portion 21 is made large enough to provide an expansion space 50 which will be of sufficient capacity to take care of any expansion caused by ordinary increases in engine temperature.

Figure 3 shows a modified type of filling means in which a tubular member 80, having its lower end closed, is suspended from the top of the radiator. Secured to the bottom portion of this tube in any suitable manner is a sleeve 82. Openings 84 are provided in the tubular member just above the point where the sleeve is secured to it. The upper end of the tubular member is provided with a tapered seat 86, and the filler cap 88 carries a stamped member 90 which is adapted to compress a gasket 92 against the tapered seat. A small vent pipe 94 is supported in the tubular member with its upper end terminating at a point on the tapered seat, and its lower end extending downwardly to the point at which it is desired to keep the liquid level when the radiator is being filled. It will be seen that during the filling operation the upper end of the vent pipe 94 is open, and the air being displaced by the liquid which is being poured into the radiator may escape through this vent pipe. As soon as the liquid level reaches a point slightly above the bottom of the pipe 94, no more air may escape

from the interior of the radiator, and the air which is therefore trapped in the header portion 21 will automatically provide an expansion space in the top of the header portion. Any additional liquid which is poured into the filler opening will merely rise in the tube 80, indicating to the operator that the cooling system has been filled to the proper level. When the cap 88 is secured in closing position over the filler opening, the gasket 92 will close the upper end of the vent pipe 94, and thereafter the only escape for pressure which may develop in the header portion is through the openings 84, the pressure forcing its way through the liquid which is trapped in the member 80 and between the latter and the sleeve 82, after which the pressure may escape to the atmosphere through the overflow pipe 76.

In the construction shown in Figure 4, a U-shaped tube 96 is used instead of the sleeve 82, as shown in Figure 3, but the operation of this form of filling device would be the same as that described above, any pressure developing in the header portion 21 escaping to the atmosphere by forcing its way through the liquid trapped in the bottom of the U-shaped tube 96, after which it may escape to the atmosphere through the overflow pipe 76.

In the form of cap shown in Figure 5, a filler cap 98 of conventional type serves to compress a gasket 100 against a flat surface 102 formed at the upper end of the tubular member 80, thus closing the upper end of the vent pipe 94. It will be obvious that the lower part of the filling device shown in Figure 5 may be constructed in either of the manners shown in Figures 3 and 4.

From the above it will be readily seen that our novel filling device will automatically provide an expansion space in the header portion of the radiator without depending in any way upon the operator's judgment. The advantages of this device are that it not only prevents the loss of cooling liquid and anti-freeze solution through the overflow pipe, but also prevents the escape of vapor which may be formed by the heat of the engine, the vapor being retained within the header portion by the water seal, and consequently becoming condensed, and the condensate returning to the cooling system for further use, whereas in the ordinary type of radiator filling device, there is nothing to prevent the escape through the overflow pipe of any vapor which may be formed.

It is thought from the foregoing taken in connection with the accompanying drawings that the construction and operation of the device will be apparent to those skilled in the art, and that various changes in size, shape and proportions and details of construction may be made without departing from the spirit and scope of the appended claims.

We claim:

1. In combination with a radiator having a header portion located at its top, a filler tube supported in one of the walls of the header portion and extending into said header portion, a cap adapted to be secured in closing position upon the top of said filler tube, a vent opening associated with said filler tube through which air may escape from the interior of the container during the filling operation, the bottom of said vent opening being located a substantial distance below the top of said header portion, said vent opening being adapted to be sealed by the liquid as soon as the latter rises slightly above the bottom of said vent opening to prevent further es- 75

cape of air from the interior of the container, thereby automatically providing an expansion space in the top of said header portion, and means associated with said cap to close the top of the 5 vent opening when the cap is secured in closing position upon said filler tube.

2. In combination with a radiator having a header portion located at its top, a filler tube supported in one of the walls of the container and 10 extending into said header portion, an overflow pipe connected with said tube and establishing communication between the interior of the tube and the atmosphere, said tube having a vent opening associated therewith through which air 15 may escape during the filling operation until the liquid reaches a predetermined level for the purpose of providing an expansion space within said header portion, said tube also having associated with it a second opening through which excessive 20 pressure within said header portion may escape to the overflow pipe, and means associated with the second opening to provide a water seal serving to normally close said second opening.

3. In combination with a radiator having a header portion located at its top, a filler tube supported in one of the walls of the header portion and extending into said header portion, a cap adapted to be secured in closing position to the top of said filler tube, and means for closing 25 the bottom end of the tube, said means being so interconnected with said cap that it will be moved to a position wherein it will close the bottom of said filler tube when the cap is applied in closing 30 position to the top of the filler tube.

35 4. In combination with a radiator having a header portion located at its top, a filler tube supported in one of the walls of said header portion and extending into said header portion, means for sealing the bottom of said tube when the radiator is in use, said tube having a pressure relief 40 opening formed in it near its lower end, and a conduit connected with the outside of said tube and communicating with said opening, said conduit extending upwardly to a point adjacent the top wall of said header portion.

45 5. In combination with a radiator having a header portion located at its top, a filler tube supported in one of the walls of said header portion and extending into said header portion, means

for sealing the bottom of the tube when the radiator is in use, said tube having a pressure relief opening formed in it near its lower end, and a sleeve extending around but spaced from said tube, said sleeve being secured to said tube below 5 the pressure relief opening and extending upwardly to a point near the top of said header portion.

6. In combination with a radiator having a header portion located at its top, a filler tube supported in one of the walls of the header portion and extending into said header portion, an overflow pipe communicating with the interior of said 10 filler tube, and a trap portion associated with said tube below said overflow pipe, said trap portion 15 being adapted to receive and hold some of the liquid poured into the radiator during the filling operation, said trap portion serving to normally prevent escape of vapors from the header portion to the overflow pipe, but permitting escape 20 of excessively high pressures from said header portion through said overflow pipe.

7. In combination with a radiator having a header portion located at its top, a filler tube supported in one of the walls of the header portion 25 and extending into said header portion, a trap portion associated with the lower end of said tube adapted to receive and hold some of the liquid 30 poured into the radiator during the filling operation, a vent opening associated with said tube to 35 permit the escape of air from the interior of the header portion during the filling operation, and means adapted to close the vent opening when the radiator is in use.

8. In combination with a radiator having a header portion located at its top, a filler tube supported in one of the walls of the header portion and extending into said header portion, said tube having an opening formed therein adjacent its lower end, a sleeve extending around but 40 spaced from said tube, said sleeve being secured to said tube below said opening, a vent opening associated with said tube to permit escape of air from the interior of the header portion during the filling operation, and means adapted to close 45 said vent opening when the radiator is in use.
